MATCH FOLDER

Robert F. Mahon, Lake Geneva, Wis., assignor
of one-half to Florence E. Macdonald, Lake
Geneva, Wis.

Application October 16, 1936, Serial No. 105,967

1 Claim. (Cl. 206—29)

My invention refers to foldable packages or envelopes containing paper or fibre matches.

The object of my invention is to provide a simple, economical, and safe jacket or envelop for such matches, the construction and arrangement of which is such that the protecting flap of the envelop is locked into engagement with a bottom lip of the same, whereby the striking strip is exposed through an opening in said bottom lip.

With this and other minor objects in view, the invention consists in certain peculiarities of construction and combination of parts, as herein-after set forth and subsequently claimed.

In the drawing,

Figure 1 represents a face view of a match package embodying the features of my invention, parts thereof being broken away to partly illustrate certain structural features, and showing the match striking strip exposed in an opening of the flap and locked in said position.

Figure 2 is a similar view, with the flap partly opened.

Figure 3 is a sectional elevation of the match package embodying the features of my invention.

Figure 4 is a magnified view of the lower section of the package, illustrating the match striking strip flush with and in locked engagement with the tongue opening.

Referring by characters to the drawing, 1 represents a jacket or envelop having a foldable flap 2, the free lower end of which flap is provided with a striking strip 3, which is spaced slightly from the bottom edge of said strip to form an engaging ledge 4, it being understood that the striking strip is rectangular in shape, and the ends are spaced from the edges of the envelop, as shown in Figure 2.

The bottom end of the envelop is folded over to form a protecting tongue 5, and fitted into the base of the protecting tongue and riveted or otherwise secured thereto, is a group of fibre matches 6. The tongue 5, as shown, is provided with a rectangular opening or window 5', which window is of the same dimensions as the striking strip 3, whereby said striking strip may be nested therein when the flap 2 of the package is in locked or in sealed engagement, whereby the matches are thoroughly protected when one of the said matches scratches over the striking strip 3.

From the foregoing description it will be seen that after a match has been extracted from the package, the strip 2 is closed down in its safety position and locked therein, due to the fact that the striking strip is nested within the opening 5', and the outer striking surface of said strip, as

best shown in Figure 4, is flush with the protecting tongue 5.

Particular attention is called to the fact, owing to the rectangular opening in the tongue 5, when the flap is closed, as shown in Figure 4, the striking emery strip is nested in the opening and is flush with the outer wall of the tongue. The flap 2, under standard conditions, is quite flimsy and thin. Hence, owing to the fact that the emery strip carried thereby in locked position relative to the tongue, the longitudinal striking pressure upon the strip 3, when locked, will prevent the flap 2, which is flimsy, from shifting to one side or the other, and thereby not only defeat the object of proper striking, but possible swinging movement will tend to tear the flap 2 at its top folded point from the back portion. Furthermore, owing to the flush connection of the interlocked parts, the emery striking strip will be protected from pressure in withdrawing the package from the pocket, or inserting it therein, and this abrasion will develop in an ordinary package, whereby the striking surface is marred for functioning. Also, in all match packages of this character, the danger of igniting the entire group of matches in striking a match before the folder is closed frequently results in serious injury and infection. The general practice in putting out matches in folders of this character is to print a warning thereon to the effect that the flap must be closed before striking a match.

It has further developed in practice that a package having a tongue with a longitudinal opening therein, into which is fitted the striking strip, there is a psychological suggestion to close it, whereby the striking strip will come into interlocked position.

Hence, there is no danger of the package becoming inadvertently opened, and when a match is ignited, owing to the fact that the striking strip is fully protected on all sides, there is practically no danger of igniting or scorching the group of unused matches.

Attention is also directed to the fact that this package as a whole can be manufactured as cheaply as the standard package of this character, and owing to its novel arrangement it will increase the effectiveness of the package as a whole against inadvertent ignition.

While I have shown and described one simple exemplification of my novel match package, it is understood that I may vary the structural features within the scope of the claim.

I claim:

A match package comprising, a group of fibre

5 matches, an envelop fitted over the same, and secured to the bottom edge thereof, the envelop being folded over the front edge of the match group to form a locking tongue having a rectangular opening therein, a striking strip carried by the envelop flap conforming to the contour of the opening in the tongue, whereby when the flap is closed said striking strip is nested in the opening

with its outer surface flush with the outer surface of the tongue, said strip forming an interlocking engagement with the walls opening to hold the package closed at the free end of the envelop flap during a scratching operation for igniting a segregated match. 5

ROBERT F. MAHON.
